Application November 9, 1942, Serial No. 465,010

6 Claims. (Cl. 93—27)

This invention relates to a method and means for heat sealing bags. More specifically this invention relates to providing an open-ended tube with a heat-sealed seam by suitable application of heat and controlled rolling pressure followed by subsequent chilling and setting of the seam under rolling pressure.

The packaging of dehydrated foods and other substances in non-metallic containers has been widely adopted recently owing to the convenience and efficiency of such packaging. In order to prevent access of moisture to the contents in such packages which will cause deterioration of the contents, it has been found that the packages must be securely and hermetically sealed. In making such packages from tubes or envelopes the production of seams which will not open or permit access of air and moisture to the contents has presented many difficulties, particularly when the tubes are formed from sheet materials coated with a heat-sealable composition so as to permit formation of seams autogenously by applying heat and pressure to the portions to be sealed.

According to the present invention the difficulties hitherto encountered in forming effective heat-sealed seams have been successfully solved by carefully controlling the conditions and sequence of steps in forming the seams.

Further details of the invention will be more fully explained by reference to the drawings and specification.

Figure 1 is a perspective view of the tube sealing unit.

Figure 2 is an elevational view taken on lines 2—2 of Figure 1.

Figure 3 is a cross-sectional view taken on lines 3—3 of Figure 1.

Figure 4 is a sectional view taken on lines 4—4 of Figure 3.

Figure 5 is a sectional view of the heat-sealed tube taken along lines 5—5 of Figure 1.

Figure 6 is a sectional view taken on lines 6—6 of Figure 2.

Figure 7 is a sectional view taken on lines 7—7 of Figure 2.

Figure 8 is a perspective view of the tube before sealing one end thereof, and

Figure 9 is a perspective view of the completed tube or bag, being partly cut away to show its sealed end.

Referring to the drawings, Figure 8 illustrates a tube 10 open at both ends made from any suitable sheet material such as paper, glassine, Cellophane (regenerated cellulose), ethyl celu-

lose, cellulose acetate and the like and coated with a suitable heat-sealable coating on both surfaces or at least on its inner surface 11 which will form an autogenous seal by application of heat and pressure. Suitable coating compositions for this purpose are, for example, disclosed in Patent Nos. 1,997,583 and 2,054,113. Any other suitable and available heat-sealable sheets may be utilized. The tube may be formed in any suitable manner by any conventional apparatus such as, for example, by continuously folding a travelling web and sealing the overlapped portions by heat and pressure alone or by means of a suitable adhesive applied to the overlapped longitudinal margins. The continuous tube so formed is then cut into open-ended tubes 10 of suitable dimension as illustrated in Figure 8. One end may be provided with a semi-circular cut-out portion 12 as a finger-grasping portion for facilitating opening of the tube after sealing same. The longitudinal side margins 13 and 14 of the tube may be subjected to heat and pressure to form autogenously sealed longitudinal seams in order to reinforce the tube at the lateral margins and to insure hermetic sealing of the contents. A bottom seam 14 is then formed as illustrated in Figure 9 in accordance with the present invention.

A spaced series of tubes 10 are continuously fed to the sealing mechanism illustrated in Figure 1 forming the subject-matter of this invention. The tubes 10 travel from the chute 16 onto an endless travelling conveyor belt 17 guided on rolls 18 and 19 supported in frame 20, moving in the direction of the arrows indicated in Figure 1. As the conveyor passes over roll 19 the tubes 10 fall onto an endless travelling conveyor 25 guided over rolls 26 and 27 moving in the direction indicated by the arrows in Figure 1. The bottom portion of the tubes 10 contact a guide bar 28 which guides the tubes into proper alignment with the bottom seam forming elements. The guide bar 28 is slightly inclined, say about 2°, toward the line of travel of the tubes 10 on conveyor 25.

The bottom seam forming elements comprise a large rotating supporting roll 30 on which a spaced series of the tubes 10 are supported while travelling continuously. Roll 30 is driven by motor 1 through belt 2 and shaft 3. As the tubes 10 leave the conveyor 25 they are guided by curved guide bar 29 and the bottom portions thereof which will form the seam 15 are brought successively into direct contact with roll 30 at which point endless belt 31 engages the suc-

cessive tubes 10 and carries them under rolling pressure into contact with roll 30. Belt 31 is carried over rolls 32, 33 and 34 which are positioned in relation to roll 30 so that belt 31 engages or coacts with roll 30 at least half of its periphery, or about an arc of 180°. Belt 31 is maintained under suitable taut tension by adjusting the position of roll 33 by any suitable tensioning means. The tension on belt 31 is adjusted so that the necessary pressure is applied to the bottom portion of tube 10 for forming an autogenously welded bottom seam 15.

on the seams by means of pressure roll 35 which is adjustably positioned so as to apply predetermined pressure directly on belt 31 which in turn is firmly pressed against roll 30. Roll 35 is positioned about the middle of the arc of travel of the tubes 10 on roll 30. The roll 30 is heated in any suitable manner. As shown in Figure 7, an internal arcuate steam jet 40 is provided internally of the roll 30 and steam is supplied to the jet through tube 41 extending through the supporting shaft 45. The condensate steam is pumped out through pipe 42 extending through the shaft.

By means of this construction the ends of the tubes 10 are heated and maintained sufficiently to a rolling or ironing pressure for a substantial period of time and supported by a roll 30 of a comparatively large diameter so that it can continuously support anywhere from 10 to 100 tubes 10. The use of the heated roll 30 and the continuous application of the heat to the tubes 10 insures a positive adhesion of the seam coating to the material 10. The tubes 10 are heated to a temperature which is sufficient to melt the adhesive and to form a seam which is substantially continuous and which is substantially heat-sealed. The tubes 10 are then cooled by a blast of cold air supplied by a blower 55 to chill the seam portion during this portion of the travel, but without application of any pressure thereto. During travel of the bags between belts 50 and 51 the bags are flattened into substantially flat planar condition.

The bags 10 are then conveyed into contact with a chilled supporting roll 60 with the seam portion 15 in direct contact with roll 60. The bottom seams of the bags are retained under pressure against roll 60 by means of endless belt 61 travelling in the direction of the arrows shown in Figure 2 coating with about half of the periphery of roll 60. Belt 61 is supported on rolls 52, 62 and 63. Roll 62 is adjustably positioned so as to regulate the tension of belt 61 in order

to control the pressure applied to the bags 10 supported on roll 60. Roll 60 is chilled in any suitable manner such as by cold circulating water which is sprayed internally as shown in Figure 6. Cold water enters through pipe 70 and escapes through sprayhead 72. The water is withdrawn through tube 73 by a suction pump. Pipes 71 and 73 are stationary and extend through the shaft 76 supporting roll 60. Rolls 30 and 60 are preferably of the same diameter and are synchronously driven by motor 1 through belts 2 and 3 as shown in Figure 1.

and the adhesive finally set or congealed while

15 subjected to rolling pressure and cold as they travel about roll 60 so that when the bags leave the roll 60 the seam is fully completed and the bag is ready for immediate use. The bags are guided from roll 60 by curved guide plate 75 and fall onto a travelling endless conveyor 76 supported on rolls 77 and 78 and thence to a supporting table 80 where the bags 10 are inspected.

20 At this point the bags may either be packed in shipping cases or conveyed directly to a filling mechanism for filling the bags with any material to be packaged. After filling the top of the bag is autogenously heat-sealed by any suitable manual or automatic means and the bag is then subjected to the rolling pressure and cold as by the means previously described for forming the bottom seam.

25 The invention is not necessarily restricted to the use of a heated roll for forming an autogenously heat-sealed seam in any type of bag. The use of a heated roll is not necessary since any seam may be needed. It is to be understood that the invention may be made in the specific embodiment or the

30 several novel features of this invention and it is to be understood that the invention is not limited to the use of a heated roll.

35 We claim a method of forming bags which consists of the steps of providing a tube with a heat-sealable sheet material, carrying the tube with the tube portion having a seam portion in contact with a heated roll, carrying the tube with the tube portion having a seam portion in contact with a chilled roll, and conveying the tube with the tube portion having a seam portion in contact with a chilled roll while chilling and applying pressure thereto to set the said seams.

40 2. Apparatus for forming bags from tubes of heat-sealable sheet material which comprises a heated supporting roll and a spaced chilled supporting roll, guide means for aligning one end of said tubes with the heated supporting roll, an endless belt coating with the periphery of said supporting roll to flex and apply pressure to said tubes for forming a seam while carried on said supporting roll, a pair of endless travelling belts for receiving the tubes from said supporting roll and conveying said tubes to said chilled supporting roll, and an endless belt coating with the periphery of said chilled roll to flex and apply pressure to said seams and convey the tubes on said supporting roll.

45 3. Apparatus for forming bags from tubes of heat-sealable sheet material which comprises a conveyor for continuously feeding a plurality of spaced tubes, a heated supporting roll and a spaced chilled supporting roll; guide means for aligning one end of said tubes with said heated

supporting roll, an endless belt coating with about half the periphery of said supporting roll to flex and apply pressure to said tubes for forming a seam while carried on said supporting roll, a pair of endless travelling belts for receiving the tubes from said supporting roll and conveying said tubes to said chilled supporting roll, and an endless belt coating with about half the periphery of said chilled roll to flex and apply pressure to said seams and convey the tubes on said supporting roll.

4. Apparatus for forming bags from tubes of heat-sealable sheet material which comprises a conveyor for continuously feeding a plurality of spaced tubes, a heated supporting roll and a spaced chilled supporting roll, guide means for aligning one end of said tubes with said heated supporting roll, an endless belt coating with the periphery of said supporting roll to flex and apply pressure to said tubes for forming a seam while carried on said supporting roll, a pressure roll for applying regulated pressure against said endless belt while in contact with said supporting roll, a pair of endless travelling belts for receiving the tubes from said supporting roll and conveying said tubes to said chilled supporting roll, and an endless belt coating with the periphery of said chilled roll to apply pressure to said seams and convey the tubes on said supporting roll.

5. Apparatus for forming bags from tubes of heat-sealable sheet material which comprises a conveyor for continuously feeding a plurality of spaced tubes, a heated supporting roll and a spaced chilled supporting roll, guide means for aligning one end of said tubes with said heated supporting roll, an endless belt coating with the periphery of said supporting roll to flex and apply pressure to said tubes for forming a seam while carried on said supporting roll, a pressure roll for applying regulated pressure against said endless belt while in contact with said supporting roll, a pair of endless travelling belts for receiving the tubes from said supporting roll and conveying said tubes to said chilled supporting roll, and an endless belt coating with the periphery of said chilled roll to flex and apply pressure to said seams and convey the tubes on said supporting roll.

6. Apparatus for forming bags from tubes of heat-sealable sheet material which comprises a conveyor for continuously feeding a plurality of spaced tubes, a heated supporting roll and a spaced chilled supporting roll, guide means for aligning one end of said tubes with said heated supporting roll, an endless belt coating with about half the periphery of said supporting roll to flex and apply pressure to said tubes for forming a seam while carried on said supporting roll, a pressure roll for applying regulated pressure against said endless belt while in contact with said supporting roll, a pair of endless travelling belts for receiving the tubes from said supporting roll and conveying said tubes to said chilled supporting roll, a blower for directing a current of air against the seams while travelling with said pair of endless travelling belts, and an endless belt coating with about half the periphery of said chilled roll to flex and apply pressure to said seams and convey the tubes on said supporting roll.

15 7. Apparatus for forming bags from tubes of heat-sealable sheet material which comprises a conveyor for continuously feeding a plurality of spaced tubes, a heated supporting roll and a spaced chilled supporting roll, guide means for aligning one end of said tubes with said heated supporting roll, an endless belt coating with about half the periphery of said supporting roll to flex and apply pressure to said tubes for forming a seam while carried on said supporting roll, a pressure roll for applying regulated pressure against said endless belt while in contact with said supporting roll, a pair of endless travelling belts for receiving the tubes from said supporting roll and conveying said tubes to said chilled supporting roll, a blower for directing a current of air against the seams while travelling with said pair of endless travelling belts, and an endless belt coating with about half the periphery of said chilled roll to flex and apply pressure to said seams and convey the tubes on said supporting roll.
